UNITED STATES PATENT OFFICE

169,933

TABLE OR THE LIKE

David Chapman, Chicago, Ill., and Richard G. Reineman, Muskegon, Mich., assignors to The Brunswick-Balke-Collender Company, Chicago, Ill., a corporation of Delaware

Application February 13, 1953, Serial No. 23,619

Term of patent 14 years

(Cl. D33—14)

To all whom it may concern:

Be it known that we, David Chapman and Richard G. Reineman, citizens of the United States, residing at Chicago, in the county of Cook, State of Illinois, and Muskegon, in the county of Muskegon, State of Michigan, respectively, have invented a new, original, and ornamental Design for a Table or the like, of which the following is a specification, reference being had to the accompanying drawing, forming a part thereof.

In the drawing:

The figure is a perspective view of a table or the like, showing our new design.

We claim:

The ornamental design for a table or the like, as shown.

DAVID CHAPMAN.
RICHARD G. REINEMAN.
